UNITED STATES PATENT OFFICE.

ALEC BROOKE, OF GLASGOW, SCOTLAND.

BUTTON.

Application filed February 7, 1922. Serial No. 534,699.

To all whom it may concern:

Be it known that I, ALEC BROOKE, of 297 Argyle Street, Glasgow, Scotland, a subject of the King of Great Britain, have invented 5 certain new and useful Improvements in Buttons, of which the following is a specification.

At present it is usual to make buttons, such as used by upholsterers and others, 10 with a solid leather, a cloth, or other covered shell or disc, and a collet or back disc through which projects, in some cases, a shank in the form of a soft pad of fabric through which a needle and thread can be 15 passed and, in other cases, a wire shank which forms a projecting staple and through which a needle and thread can be passed. In cases where the button is provided with a soft fabric shank the latter is apt to be 20 torn in the sewing and also to readily break away in use. In cases where the button has a projecting wire shank the latter, owing to the fact that the upholsterer's needle has to be passed therethrough, must 25 project some distance from the body of the button with the result that the button is apt to split or tear the upholstery cloth if closely secured thereto. In some cases the buttons are made with stamped metal shanks having 30 holes for the passage of the needle and thread. With buttons made with shanks as aforesaid some time is absorbed in the threading operation.

The object of the present invention is to 35 make a button of the shank type in such manner that it can be very quickly attached to the thread or twine without the usual threading operation and can also be held closely and neatly against the fabric without 40 danger of tearing it. This object is attained by making the button with a double-hook shank instead of the usual staple shank, the hooks being arranged side by side and held in place by the collet in such 45 manner that, together, they constitute an eye with side gaps or openings, oppositely disposed, for the entry of the thread. The button is threaded, not by passing a needle and thread into or through the shank, as 50 usual, but by simply causing the hooks of the button to engage the thread, this being done, in the simplest way, by causing the thread to first pass between the hooks and then giving the button a partial turn. In 55 the case of upholstery work the thread (or

twine) can be held taut between the hooks and the button secured to, or on, the thread by giving it the partial turn as aforesaid; the thread, in this way, being held in the eye constituted by the two hooks. Of course, in the same way, a thread or twine can be secured to the button.

In order that the invention may be clearly understood I have hereunto appended explanatory drawings which show, by way of example, one mode of constructing the improved button.

Figs. 1 to 4 show, respectively, in end elevation, plan, side elevation and section, a button with the double hook shank.

Figs. 5 to 7 show the method of securing the thread to the button, and Fig. 8 is a detail.

As will be seen the button *a* has at its back two hooks, *b*, *c*, arranged side by side at a short distance apart and held in place by the collet *d*. In the example shown the hooks are oppositely inclined to the face of the collet and form parts of a single piece of wire as indicated in dotted lines. Each hook curves down so as to almost touch the back of the button just sufficient space being left for the thread or twine, as the case may be, to pass through the gap into the inside of the hook. The hook ends may be bent laterally slightly as shown.

When securing a button to a thread or twine *e* (or vice versa) the thread is first caused to enter the space between the parallel hooks *b*, *c*, (as at Fig. 5) until it rests 90 against the collet *d* whereupon the button is turned in the direction of the arrow, through 90°, and, automatically, the thread passes through the gaps at *g* and *h* left between the ends of the hooks and the collet 95 and becomes threaded through the eye (formed by the two hooks) as at Figs. 6 and 7. It will be seen the position of the hooks in Fig. 6 is at right angles to the position, Fig. 5.

Having now fully described my invention what I claim and desire to secure by Letters Patent is:—

1. A button comprising a body part and a shank, the latter consisting of two oppositely disposed hooks spaced apart and arranged side by side, the hooks forming an eye.

2. A button comprising a body part and a shank, the latter consisting of two oppo-

100

105

110

sitely disposed spaced apart hooks arranged side by side, the hooks being oppositely inclined and cooperating to form an eye.

3. A button, including a body portion and

5 a shank, said shank being formed of two oppositely disposed hooks located side by side and having laterally bent end portions, said hooks cooperating to form an eye and the bent ends being adapted to squarely en-

10 gage the thread to be inserted in the eye in the turning movement of the button.

4. A button comprising, in combination, a body part, a collet having a central opening therein and a single length of wire se-
15 cured beneath said collet and having its ends projecting through said opening and bent in

such manner that, together, they constitute an eye with oppositely disposed side gaps or openings for the entry of the thread or twine.

5. A button comprising, a body part and a shank, the latter consisting of two oppositely disposed hooks arranged side by side so that they constitute an eye with side gaps or openings for the entry of the thread or 25 twine.

In testimony whereof I affix my signature in presence of two witnesses.

ALEC BROOKE.
